(57) **CLAIM**

I claim the ornamental design for a combined protective cuffed jewelry sleeve and secured jewelry display board insert, as shown and described.

DESCRIPTION

FIG. 1 is a front elevational view of a combined protective cuffed jewelry sleeve and secured jewelry display board insert with the display board element removed from the jewelry sleeve element illustrating an embodiment of my new design;

FIG. 2 is a front perspective view thereof;

FIG. 3 is a front elevational view thereof with the display board element disposed within the jewelry sleeve element; FIG. 4 is a front elevational view thereof with the protective cuff lifted to show a concealed handle underneath;

FIG. 5 is a rear perspective view thereof;

FIG. 6 is a rear perspective view thereof with a loop having mesh attached thereto flipped out of the jewelry sleeve element;

FIG. 7 is a front perspective view thereof;

FIG. 8 is a front elevational view thereof with the protective cuff inverted to close the jewelry sleeve element and reveal the handle;

FIG. 9 is a rear elevational view thereof;

FIG. 10 is a top perspective view thereof;

FIG. 11 is a front perspective view thereof with the display board element removed from the jewelry sleeve element; FIG. 12 is a bottom perspective view of the display board element thereof;

FIG. 13 is a top perspective view thereof;

FIG. 14 is a front elevational view thereof;

FIG. 15 is a front perspective view thereof with clasp loops partially unfurled;

FIG. 16 is a front elevational view thereof with a single clasp loop partially unfurled;

FIG. 17 is a rear perspective view thereof with clasp loops partially unfurled; and,

FIG. 18 is a rear elevational view thereof with clasp loops secured.

The elements of the claimed design are shown detached for clarity of illustration.
